(57) **CLAIM**

The ornamental design for a ventilated canopy for a vehicle, as shown and described.

DESCRIPTION

FIG. 1 is a top perspective view of a first embodiment of a ventilated canopy for a vehicle, showing my design;
FIG. 2 is a top view of the first embodiment;
FIG. 3 is a front view of the first embodiment;
FIG. 4 is a rear view of the first embodiment;
FIG. 5 is a left side view of the first embodiment, the right side view being a mirror image thereof;
FIG. 6 is a top perspective view of a second embodiment of a ventilated canopy for a vehicle, showing my design;
FIG. 7 is a top view of the second embodiment;
FIG. 8 is a front view of the second embodiment;
FIG. 9 is a rear view of the second embodiment;
FIG. 10 is a left side view of the second embodiment, the right side view being a mirror image thereof;
FIG. 11 is a bottom view common to both embodiments;
FIG. 12 is a bottom view common to both embodiments, with the fan bracket portion removed so as to show the aperture in the canopy;
FIG. 13 is a bottom perspective view of the fan bracket portion shown separately for clarity of disclosure this bracket is common to both embodiments;
FIG. 14 is a bottom view of the fan bracket portion, the top view being a mirror image thereof;
FIG. 15 is a left side view of the fan bracket portion, the right side view being a mirror image thereof;
FIG. 16 is a front view of the fan bracket portion; and,
FIG. 17 is a rear view of the fan bracket portion.
In the drawings, the broken lines depict a fan and form no part of the claim.
